UNITED STATES PATENT OFFICE.

EDWARD M. CRANE, OF OSHKOSH, WISCONSIN.

DESIGN FOR AN OSCILLATING BODY-LOOP FOR VEHICLES.

SPECIFICATION forming part of Design No. 31,089, dated June 27, 1899.

Application filed May 31, 1899. Serial No. 718,920. Term of patent 7 years.

To all whom it may concern:

Be it known that I, EDWARD M. CRANE, a citizen of the United States, residing at Oshkosh, in the county of Winnebago and State 5 of Wisconsin, have invented and produced a new and original Design for Oscillating Body-Loops for Vehicles; and I do hereby declare the following to be a full, clear, and exact description of the same, reference being had to 10 the accompanying drawings, forming a part thereof.

In the accompanying drawings, Figure 1 is a perspective view of an oscillating body-loop for vehicles embodying my design, and Fig. 15 2 is a perspective view looking at the same from the rear.

The leading feature of my invention consists of a laterally-extending oscillating body-loop having a front arched portion provided 20 with a centrally-arranged downwardly-extending attaching bracket or ears and rearwardly-extending attaching portions at the ends of the front arched portion.

A in the drawings represents my oscillating

body-loop for vehicles, which is formed with 25 a front arched portion a and rearwardly-extending attaching portions a' , by means of which the body-loop can be attached to the body of a vehicle. The front arched portion a is provided with a downwardly-extending 30 attaching bracket or ears a^2 , by means of which the body-loop can be secured in an oscillating manner around the upper half of an elliptic spring, so that the pivot-point will be below the said upper half.

Having now described my invention, what I claim as new, and desire to secure by Letters Patent, is—

The design for an oscillating body-loop for vehicles, substantially as herein shown and 40 described.

In testimony whereof I hereunto affix my signature in presence of two witnesses.

EDWARD M. CRANE.
